BUDGET BOX

Ethel L. Cummings and Millard M. Cummings,
St. Louis, Mo.

Application April 21, 1947, Serial No. 742,983

4 Claims. (Cl. 161—1)

1

This invention relates to a device for facilitating budgeting, its principal object being to provide such a device, which we have called a "budget box," by which a person may at the beginning of the week not only lay aside sufficient money to take care of the week's needs, but also keep the allotment for each single day's necessities separate from the rest of the week's supply of money.

Almost everyone knows at the beginning of a week about what his expenses for that week will amount to, and also what his day by day expenses will be. For instance, Tuesday may be the day on which he must pay his gas bill, and perhaps on Thursday he plans to entertain friends, which will entail an expense; and so on, and he can pretty well foresee at the beginning of the week what he will need in the way of money. Through the use of our budget box he can place in one of a set of seven compartments provided therefor the money he expects to spend on Monday, Tuesday, Wednesday, Thursday, Friday, Saturday, and Sunday, respectively, there being a separate compartment for each day, and all of the compartments being then locked and controlled by a clock mechanism so timed as to open the compartments, one after another, at twenty-four hour intervals; that is to say, the clock mechanism is set, for example, to open the Monday compartment on Monday morning, the other compartments remaining locked, and on Tuesday morning the second, or Tuesday, compartment will open, and so on throughout the week.

An additional compartment is provided for savings, and this is intended to receive any surplus of money that might remain at the end of any day, should the allotment for that day's needs exceed expenses, and this savings compartment will open simultaneously with the opening of the compartment for the last day of the week. In a drawer, which is independent of the clock mechanism and always accessible, there may be placed a sum of money for emergencies which were not anticipated when the allotments for the seven days of the week were placed in the seven compartments.

An advantage of our budget box is that it guards a person using it against inadvertently spending in a week in excess of what he should permit himself to spend, with reference to the amount of his income, and the daily savings feature helps to create a reserve fund and thus inspires the user to greater thrift. Also, there are many people who will spend thoughtlessly and unnec-

2

essarily small amounts of money when these are easily accessible, and for such people our budget box provides beneficial restraint and tends to inculcate the habit of carefulness in spending.

Fig. 1 is a perspective view of our budget box as it appears with the compartments locked and ready for operation, and with the lid of the box in raised position.

Fig. 2 is a top plan view of the open budget box, showing the clock mechanism, some of the compartments being open and some closed, the view being partly broken away to show the mechanism for controlling the locking feature of the compartments.

15 Fig. 3 is an enlarged detail view taken on line 3—3, Fig. 2.

Fig. 4 is an enlarged detail view taken on line 4—4, Fig. 2, showing a part of the locking mechanism in locked position.

20 Fig. 5 is an enlarged detail view taken on line 5—5, Fig. 2, showing part of the locking mechanism in open position.

Fig. 6 is an enlarged detail view taken on line 6—6, Fig. 4.

25 Fig. 7 is an enlarged detail view taken on line 7—7, Fig. 4.

Fig. 8 is an enlarged detail view taken on line 8—8, Fig. 2.

The invention comprises a box having a front 30 wall 1, a rear wall 2, end walls 3 and 4, respectively, a floor which is not visible in the drawings, and a hollow lid 5 hinged to the rear wall of the box, as at 6. The box may be formed of any suitable material, and a narrow strip 7 of the 35 same material is secured against the outside of the front and end walls of the box at their upper portions and extends slightly above the box, as shown at B in Fig. 1, so that when the lid 5 is closed it rests on the top edge of the walls of the 40 box and within the strip 7.

The interior of the box is divided into ten compartments, as follows: Compartment 8 at one end of the box extends transversely from front to rear of the box its full depth; compartment 9 extends longitudinally of the box from the side of compartment 8 to the end wall 4, and is comparatively shallow, its depth being approximately half the depth of the box; compartments 10, 11, 12, 13, 14, 15, 16, and 17 extend transversely of the box from the rear wall thereof to the compartment 9. The compartments 8 and 10 to 17, inclusive, are provided with closure members 8' and 10' to 17', respectively, each closure having a longitudinally extending slot 18. 55 All of the compartments are shown in Fig. 2,

the compartments 8, 15, 16, and 17 being open, and the compartments 10, 11, 12, 13, and 14 being covered by their closure members 10', 11', 12', 13', and 14', respectively. Under the compartment 9, extending its full length and from the compartments 10 to 17, inclusive, to the front wall 1 of the box we provide a space for the reception of a drawer D having a knob C for convenience in pulling out the drawer (Fig. 1). The drawer D is a repository for money to be used in an emergency.

A clock mechanism, which I have designated generally by the letter A, is positioned within the compartment 8, but since this mechanism may be of any suitable type and does not constitute a part of the present invention, it will not be further described except to say that it is adapted to be regulated for the opening of the various compartments at predetermined intervals, as mentioned in the opening remarks of this specification.

The locking mechanism of our budget box is contained in the compartment 9, and consists of the following parts:

A cylindrical rod 19 extends from end to end of the compartment 9 and is mounted on and rotatable with a shaft 20, which is secured in one end wall of said compartment and extends through its opposite end wall into the compartment 8. A wheel 21 is rigidly mounted on the end of the shaft 20 which extends into the compartment 8 and is rotatable with said shaft, and between the wheel 21 and the end wall of the compartment 9 a gear wheel 22 is also rigidly mounted on and rotatable with the shaft 20, the gear wheel 22 meshing with a larger gear 23 which is connected with the clock mechanism A, so that when the clock mechanism is in operation it will impart motion to the gear 23 and its meshing gear 22, and thus through the shaft 20 to the wheel 21 and to the rod 19. From the above it will be understood that the parts 21, 22, and 23, which are located in the compartment 8, are not an actual part of the locking mechanism in compartment 9, but serve to activate the locking mechanism, as will be later explained.

On the rounded surface of the rod 19 a plurality of small ears 24 is positioned so that there will be one ear 24 opposite each of the compartments 10 to 17, inclusive, the ears being set diagonally on said rod, as shown in Fig. 2. Slightly spaced away from the rod, an elongated, rectangular bar 25 extends from end to end of the compartment 9, and on the upper surface of said bar a plurality of fingers 26 is provided, each finger 26 being swingably held in position on the bar 25 by a pin 27, and the fingers being so spaced apart that there will be one finger opposite each of the ears 24 and engageable therewith at predetermined times. At its end nearest the ear 24, each finger is rounded on one side, as shown most clearly at 28 in Fig. 2, and in its rounded end each of the fingers has a slot 29 extending inwardly a short distance from one of its sides.

In the vertical face of the bar 25 which is nearest the rod 19, and near the top of this face, we place a plurality of small screws or nails having heads 30, and near the bottom of this face of the bar 25 we place a plurality of pins 31, so that each pin 31 is spaced below one of the nail heads 30 and at an angle thereto. A section of spring wire 32 is engaged with said nail head 30, pin 31, and a finger 26 by securing one end of said wire tightly under the nail head 30, then passing said wire around the pin 31, and then

leading the wire up to the finger 26 and catching the free end of the wire 32 in the slot 29 of said finger. We provide one nail head 30, one pin 31, and one wire 32 for engagement with each of the fingers 26, and thus it will be understood that there is one of these assemblies for each of the compartments 10 to 17, inclusive. The assembly just described is clearly illustrated in Fig. 7.

On the inner surface of the wall 9' of the compartment 9 we mount a series of eight elements 32a, each of which is swingable on a headed pin 33 secured in said wall, so that there is one of the elements 32a for each of the compartments 10 to 17, inclusive, and slidably mounted on screws 34 in said wall 9' a strip 35, preferably of any suitable metal, lies adjacent the wall 9' and between said wall and the elements 32a and spaced slightly above the pins 33. A section of spring wire 36 is engaged with each of the swingable elements 32a in the following manner: One end of the wire 36 is bent around the element 32a, as at 37, then wound around the shank of the pin 33, and then its free end is bent diagonally to rest on an offset 38 on the wall 9', as at 39.

We will now describe the closure members 10' to 17', and since they are identical we will refer to a single closure member for facility of description. Each of the closure members is in the form of a thin plate of any suitable material and is of generally rectangular shape, and of such width as to fit snugly between the side walls of its compartment. At its rear extremity the closure member has a small, outwardly extending tongue 40 adapted to be positioned within a corresponding cut-out 41 in the rear wall of the compartment. The closure member is of such length as to extend from the rear wall of its compartment to the sliding strip 35, so that when the tongue 40 is pushed into its cut-out 41 and the closure member is pressed down, it will not only cover its particular compartment but also extends to the front wall of the compartment 9 (Fig. 1). On the underside of the closure member we provide a hook 42 which is adapted to engage the free end of the finger 26 which is opposite its particular compartment at predetermined times, as will be hereinafter set forth, the free end of the finger 26 being so shaped as to conform to the shape of the hook. Each of the closure members is furnished with a knob K by which it may be lifted, and the slots 18 in the closure members, which have been previously referred to, are diagonally cut as shown in Fig. 8.

The closure member 8' for the compartment 8 is of rectangular shape and of such dimensions as to completely cover said compartment, and has an opening 43 through which characters on the circumference of the wheel 21 may be observed. An elongated closure is provided for the compartment 9, and consists preferably of a metallic strip bent at a right angle to form a horizontal face 44 which covers the compartment 9 and lies underneath the forward ends of the closure members 10' to 17', inclusive, and a vertical face 45 which depends between the wall 9' of said compartment 9 and the free ends of the fingers 26. The face 44 has a plurality of apertures 46, one of said apertures being situated above each of the fingers 26.

Inside the lid 5 and opposite each of the compartments 10 to 17, inclusive, a clip 47, preferably of spring metal, is secured to the lid, for the purpose of retaining near each compartment any memoranda concerning the expenses of other activities relating to that day.

In the use of our budget box the procedure is as follows:

The compartments 10 to 16, inclusive, are intended respectively for the seven days of the week from, say, Monday to Sunday, inclusive, and at the beginning of the week the user places in the various compartments the amount of money he expects to spend on the different days of that week. When the money has been deposited in the seven compartments, each of the closure members 10' to 17', inclusive, is positioned above its compartment with its tongue 40 in its cut-out 41, and its hook 42 above an aperture 46. The slideable strip 35 has a series of eight inwardly extending pins 48, one of which is positioned adjacent each of the swingable elements 32^a, and at one end of said strip 35 it has an upstanding extension 49 by which it may be grasped to impart sliding movement to said strip, and this sliding movement pushes the slideable elements 32^a to a diagonal position by virtue of their contact with the pins 48, thus bringing the beveled ends 50 of said elements 32^a into substantially horizontal position. With the parts just mentioned in this position, the hooks 42 are pushed down through the apertures in the horizontal face 44 of the closure for the compartment 9, so that said hooks will engage the free ends of the fingers 26, which obviously retains the closure members in locked position to close the compartments 10 to 17, inclusive. The strip 35 may then be retracted, but the closure members 10' to 17', inclusive, pressing down upon the swingable elements 32, will hold said elements in diagonal position and exerting pressure on the closure members through the action of the spring wire 32. The closure member 8' is placed in position to close compartment 8, but this closure is not connected with the locking arrangement just described.

With the money compartments now closed and locked, the clock mechanism is set in operation to open them one after another at twenty-four hour intervals, as follows:

As said before, the wheel 21 is connected to the clock mechanism through the gears 22 and 23, so that when the clock mechanism is wound it operates to revolve the wheel 21 through said gears. Characters, either the figures 1 to 7, inclusive, or the initials of the days of the week, are applied to the circumference of the wheel 21 and may be observed through the opening 43 in the closure 8' (Fig. 1), and these characters are so spaced that the one relating to the particular compartment being opened will be visible at all times.

As the wheel 21 revolves, it turns with it the rod 19, on which the ears 24 are mounted, and the clock mechanism is set in any well known manner at such a rate of speed that the ears 24 will consecutively engage the fingers 26 opposite them at twenty-four hour intervals, beginning with the ear and finger opposite the Monday compartment 10. As the ear 24 contacts the rounded end 28 of the finger 26, it swings said finger so that its free end is disengaged from the hook 42, and this permits the element 32^a to push up the end of the closure 10' by virtue of the upward pressure which said element 32^a exerts through the spring wire 36. The closure may then be lifted from the Monday compartment 10 and the money removed therefrom.

At the end of the next twenty-four hours, this procedure is repeated with respect to the Tuesday compartment 11, and so on throughout the week, until on Sunday both the Sunday compartment

16 and the Savings compartment 17 will be simultaneously opened, and if there has been a surplus of money on any preceding day and such surplus has been deposited in the Savings compartment 17, it may then be removed.

After a hook 42 has been released from its engaging finger 26, said finger is swung back to its initial position through the action of the spring wire 32, and is ready for the next locking operation.

If preferred, the money for each day may be deposited in the various compartments through the slots 18 after the compartments have been locked, and the diagonal cutting of said slots is designed to make it extremely difficult to shake money out of the compartments once they have been locked.

From the above description it will be understood that on each day of the week the money which has been laid aside for the planned expenditures of that day will be available, without possibility of encroachment on the supply for the other days, as there is no way of opening the compartments manually short of damaging the budget box.

We claim:

1. A budget box comprising compartments for money and cover plates for said compartments, said cover plates having retaining means, elements for engagement with said retaining means to hold said cover plates in closed position, clock mechanism and a member operable thereby for releasing said retaining means from said elements at predetermined intervals, upstanding, swingable elements and a lever for swinging said elements to a diagonal position, and springs for returning said swingable elements to their upright position upon retraction of said lever, said swingable elements being adapted to raise said cover plates upon reaching their upright position.

2. A budget box comprising compartments for money and cover plates for said compartments, said cover plates having retaining means, elements for engagement with said retaining means to hold said cover plates in closed position, clock mechanism and a cylindrical member rotatable thereby, projections on said cylindrical member for releasing said retaining means from said elements at predetermined intervals, upstanding, spring-controlled, swingable elements and a lever for swinging said elements to a diagonal position, said elements being adapted to return to their upright position upon retraction of said lever to raise said cover plates.

3. A budget box comprising compartments for money and cover plates for said compartments, said cover plates being provided with hooks on their undersides, elements for engagement with said hooks to hold said cover plates in closed position, clock mechanism and a cylindrical member rotatable thereby, projections on said cylindrical member for engagement with said elements for releasing said hooks from said elements, said projections being so positioned that said hooks will be consecutively released at predetermined intervals, upstanding, spring-controlled, swingable elements and a lever for swinging said elements to a diagonal position, said elements being adapted to return to their upright position upon retraction of said lever to raise said cover plates.

4. A budget box comprising compartments for money and cover plates for said compartments, said cover plates being provided with hooks on their undersides, swingable, spring-controlled elements for engagement with said hooks to hold

said cover plates in closed position, clock mechanism and a cylindrical member rotatable thereby, projections on said cylindrical member for engagement with said elements to release said hooks from said elements, said projections being diagonally positioned at certain points on said cylindrical member so that said elements will be successively engaged thereby at predetermined intervals, upstanding, spring-controlled, swingable elements and a lever for swinging said elements to a diagonal position, said elements being adapted to return to their upright position upon retraction of said lever to raise said cover plates.
